RADAR SYSTEM AND ANTENNA THEREFOR

Raymond G. Herb, Boston, Mass., assignor, by
mesne assignments, to the United States of
America as represented by the Secretary of War

Application October 10, 1945, Serial No. 621,569

11 Claims. (Cl. 250—33.65)

1

This invention relates to antennas for radio object-locating systems and more particularly to an antenna having a reflector and radiating means for illuminating the reflector.

One of the objects of the invention is to provide an antenna having a parabolic reflector with a novel means for radiating and receiving radiant energy in such manner that the elevation angle of a target may be determined without requiring vertical motion of the reflector or of the antenna.

Another object of the invention is to provide in an antenna, having reflecting means and radiating means, means for producing a desired radiation pattern including one in which the energy distribution approximates the relationship $csc^2\theta$ in one plane, generally the vertical plane where θ is the angle measured from the axis of directivity of the reflecting means.

For a better understanding of the invention together with other and further objects thereof, reference is had to the following description, taken in connection with the accompanying drawing.

In the drawing:

Fig. 1 is a perspective view of a typical antenna according to this invention;

Fig. 2 is a perspective view of the feed line and novel radiating means according to one embodiment of the invention;

Fig. 3 is a diagrammatic sectional view along the line 3—3 of Fig. 2;

Fig. 4 is a diagrammatic sectional view of the feed line of Fig. 2 illustrating the positions of the exciting means and also the direction of the principal E-vector of energy within the feed line; and

Fig. 5 is a diagrammatic side elevation of the antenna of Fig. 1 illustrating the radiation pattern produced thereby and geometry of the invention.

Referring now to Fig. 1, there is shown an antenna comprising a reflector 10 which may be of any suitable conformation such as a paraboloid of revolution, a truncated paraboloid, or a parabolic cylinder or any other suitable shape to direct energy from or to a radiating element. As shown, reflector 10 is, for example, a truncated paraboloid supported on a base 11 and, if desired, in such manner that reflector 10 may be rotated about either a vertical or horizontal axis, or both. For simplification of description, it is assumed herein that reflector 10 is immovably secured to base 11 with the plane of its aperture vertical and with the longitudinal axis thereof horizontal. A radiating element 12 is mounted in front of and

2

at a suitable distance from reflector 10 for illuminating the latter.

According to this invention, radiating element 12 comprises a hollow pipe waveguide 13 of substantially circular cross-section adapted to support only the $TE_{1,1}$ mode of energy and is disposed with its axis perpendicular to the focal axis of reflector 10. In the arrangement as shown in Fig. 1, waveguide 13 is disposed with its axis vertical and is supported in any suitable manner such as by brackets 14 secured to waveguide 13.

Waveguide 13 (Figs. 2 and 3) is electrically connected at or near one end (in this case the lower end) with apparatus for transmitting and receiving waves of electromagnetic energy. Thus, waveguide 13 is provided with coupling means 15 for connection with the transmitting apparatus as indicated by T and coupling means 16 and 17 for connection with two receiving apparatus designated R_1 and R_2 respectively. Coupling means 15, 16, and 17 may be of any suitable design for exciting and picking up energy within waveguide 13. For example, means 15 may comprise an exciting probe 15' fed by a waveguide or transmission line 15'' while coupling means 16 and 17 may be in the form of pick-up probes or loops 16' and 17' coupled to transmission lines 16'' and 17''. Transmission lines 15'', 16'' and 17'' may be of the hollow pipe waveguide or coaxial conductor type. Means 15, 16 and 17 are preferably spaced circumferentially about waveguide 13 in such manner that the axis of the coupling loops or probes 15', 16' and 17' (Fig. 3) extend radially into waveguide 13 for a purpose more clearly described hereinafter.

Arranged along a portion of the length of waveguide 13 are a plurality of aligned dipoles 18. As shown more clearly in Fig. 2, there are 10 dipoles 18₁—18₁₀ arranged in a vertical straight line 40 so that a plane passing through the longitudinal axis of waveguide 13 and the row of dipoles 18 will contain the focal axis of reflector 10 and is substantially perpendicular to the aperture plane of reflector 10, with the row of dipoles 18 being disposed nearest reflector 10.

Radiating element 12 may be disposed in any desired position along the axis of waveguide 13 depending upon the shape of the desired pattern and whether the main path of the desired beam 50 pattern is to be directed ahead of the reflector or above or below the reflector axis. Thus, for airborne use with the antenna depending for example from the belly of an aircraft, it is desired to direct the radiation pattern in a downward direction or toward the ground. For such

use, radiating element 12 would be disposed above, or at least with the majority of the dipoles 18 above, the reflector axis. However, the principal application of an antenna as herein described is in searching for, or tracking of, airborne targets from a ground station. Thus, as shown in Figs. 1 and 5, radiating element 12 is disposed below the axis H of reflector 10 or with the majority of dipoles 18 below the axis H and preferably with the uppermost dipole 18, on or slightly below axis H at the approximate focal point F. For simplification of description and by way of example, the description of the invention herein is directed to such an arrangement.

Dipoles 18 may be of any conventional design adapted to radiate and receive waves of electromagnetic energy towards or away from reflector 10. Energy to and from each of dipoles 18 is transmitted by means of a transmission line 19 and by a stub line 20 preferably angularly disposed relative to the line 19, lines 19 and 20 preferably being of the coaxial conductor type as shown (Fig. 3). Each stub line 20 is coupled to the region of propagation within waveguide 13 by means of a radially disposed probe 21 adapted to excite or pick-up energy in waveguide 13.

While dipoles 18₁-18₁₀ are arranged in a straight line along waveguide 13, probes 21 are so arranged that successively they enter waveguide 13 at gradually increasing angles or gradually increasing circumferential distances toward one end of waveguide 13 relative to the position of their respective dipoles (Fig. 4). Preferably, the probe 21 at the uppermost end of waveguide 13 is disposed at a small or 0 angle with respect to its corresponding dipole 18₁, while the remaining probes 21 are disposed in turn at increasing angles or circumferential distances relative to their corresponding dipoles, with the probe 21 nearest the lowermost part of waveguide 13 being preferably approximately 90° from its corresponding dipole 18₁₀. The relative position of the dipoles 18 and their respective probes 21 is accomplished by making the connecting transmission lines 19 progressively longer and preferably curving the same to follow the contour of waveguide 13.

Assuming that the exciting probe 15' of coupling means 15 is substantially in alignment with the row of dipoles 18 and with probe 21 coupling dipole 18₁ to waveguide 13, the maximum E-vector (designated E in Fig. 4) or the E-vector in the axis of symmetry of the TE_{1,1} mode within waveguide 13 will be substantially coincident with the 0°-180° line or in other words, coincident with the radius to probe 21 serving dipole 18₁. Thus, probe 21 of uppermost dipole 18₁ will be strongly coupled to the electrostatic field in the waveguide 13 while the remaining probes 21 will have relatively and progressively weaker coupling and probe 21 for the lowermost dipole 18₁₀ will have very weak coupling.

Therefore, when the antenna is being utilized for radiation of energy, the intensity or amplitude of radiation from dipoles 18 and of the intensity of illumination of reflector 10 is tapered due to the graduated coupling of probes 21, the greater intensity being radiated from the uppermost dipole 18₁, and the least from the lowermost dipole 18₁₀. By properly adjusting the depth of penetration of probes 21 into waveguide 13, any desired resultant radiation pattern may be produced including one of $csc^2\theta$ configura-

tion as indicated by the solid line pattern in Fig. 5.

On reception of energy, such as return of echo pulses from targets, the maximum energy returned from a low target and rereflected by reflector 10 will be received by the upper dipoles 18 while that from the high targets will be received by the lower dipoles 18. Thus, from Fig. 5, it will be seen that the energy returned by a target T₁ of high elevation is reflected by reflector 10 and will be received by and excite maximum energy in dipole 18₁₀, also the energy from a target of low elevation T₂ will be returned with maximum intensity to dipole 18₁, the returning energy being indicated by broken lines in Fig. 5. Since the elevation of the target with reference to the antenna determines which of dipoles 18 receives most of the incoming energy and since each dipole excites energy in waveguide 13 through probe 21 with a characteristic polarization determined by the relative circumferential position of the respective probes 21, the resultant direction of the E-vector of the energy excited in waveguide 13 is a function of the elevation angle of the target. Fig. 4 shows the orientation of the maximum E-vector when maximum energy intensity is received by dipole 18₅, the position of which is shown in Fig. 3. By placing the two receiver channels or coupling means 16 and 17 in spaced circumferential relation about waveguide 13 as disclosed hereinbefore, the orientation of the electrostatic field in waveguide 13 and consequently, the elevation of the target can be found by comparison on a suitable indicator 22 of the magnitudes of the two received outputs. Any suitable known type of receiver may be utilized with the antenna as herein described ranging from those having two complete amplifiers to those with a single detector and amplifier with the addition of a switch or delay line to separate the energy pulses to be compared.

While the present invention has been particularly described with the radiating element 12 oriented vertically to determine elevation, it will be understood that by orienting the antenna conducting the radiating element 12 horizontally, the angle of a target in azimuth may also be determined.

What is claimed is:

1. A system comprising an antenna having a parabolic reflector and a waveguide of circular cross-section adapted to entertain the TE_{1,1} mode of electromagnetic energy, said waveguide being positioned with its axis substantially perpendicular to the focal axis of said reflector, a plurality of aligned and equally spaced dipoles arranged along a portion of the length of said waveguide and parallel to the waveguide axis, means for coupling each of said dipoles to the region of propagation within said waveguide, one of said coupling means being substantially aligned radially with the first of said aligned dipoles, each of said remaining coupling means being spaced circumferentially about said waveguide from its respective dipole, the spacing between said remaining coupling means and said dipoles progressively increasing toward one end of said waveguide and away from said first dipole, means electrically connecting said dipoles and said coupling means and supporting said dipoles, and means for exciting energy in the TE_{1,1} mode in said waveguide, said exciting means being positioned near one end of said waveguide in alignment with one of said coupling means, whereby

the latter is adapted to have maximum coupling and the remaining coupling means have relatively weaker coupling to the energy excited in said waveguide resulting in unequal intensity of energy radiated from said dipoles for producing an unsymmetrical radiation pattern.

2. The system defined in claim 1 wherein each of said coupling means includes a probe extending radially into said waveguide, the depth of penetration of said probes determining the radiation intensity from each of said dipoles and thus producing a desired pattern of radiation from the antenna.

3. The system defined in claim 1 wherein said coupling means are adapted to be so arranged relative to the electromagnetic field of energy within said waveguide that the energy distribution pattern radiated by said antenna varies substantially as the square of the cosecant of the radiation angle measured from the axis of directivity of said reflector.

4. A system defined in claim 1 wherein said means to excite said wave guide may be periodically energized whereby a pulse may be transmitted by said antenna, said dipoles being so positioned relative to said reflector that radiant energy returned as an echo to said antenna by a target is directed by said reflector onto said aligned dipoles, the angle of elevation of said target determining which one of said dipoles receives, and which of said coupling means excites in said waveguide, energy of maximum intensity, the relative position of said last-mentioned coupling means thereby determining the orientation of the maximum E-vector of energy in said waveguide, and wherein two coupling means are spaced from each other about one end portion of said waveguide, said two coupling means being adapted to be excited by said energy in said waveguide, the orientation of the maximum E-vector determining the relative intensity of energy picked up by said two coupling means, whereby, by comparison of the outputs of said two coupling means, the orientation of the maximum E-vector and consequently the elevation of the target is determinable.

5. A system for radiating and receiving waves of electromagnetic energy comprising in combination, a parabolic reflector and a waveguide of substantially circular cross-section for entertaining the TE_{1,1} mode of energy propagation, said waveguide being positioned with its axis substantially perpendicular to the focal axis of said parabolic reflector near the focal point thereof, a plurality of aligned dipoles arranged along a portion of the length of said waveguide and parallel to said waveguide axis, means for coupling each of said dipoles to the region of propagation within said waveguide, one of said coupling means being substantially aligned radially with the first of said aligned dipoles, each of the remaining coupling means being spaced circumferentially about said waveguide from its respective dipole, the spacings between said coupling means and said dipoles progressively increasing towards one end of said waveguide and away from said first dipole, means electrically connecting each of said dipoles to its coupling means, means for exciting energy in the TE_{1,1} mode within said waveguide, said exciting means being so positioned that the maximum E-vector of the energy excited thereby is in radial alignment with one of said coupling means, and output means coupled to said waveguide responsive to the orientation of the maximum E-vector pro-

duced by received energy for determining the elevation angle of said received energy.

6. A system comprising an antenna having parabolic reflecting means, a waveguide of suitable shape and dimensions for entertaining the TE_{1,1} mode of electromagnetic energy, a plurality of dipoles arranged to constitute a linear antenna array along a portion of the length of said waveguide, means positioning said array in a plane substantially perpendicular to the focal axis of said reflecting means, means for periodically exciting energy of the TE_{1,1} mode in said waveguide, whereby a pulse will be radiated by said antenna, means for coupling each of said dipoles to the region of energy propagation within in said waveguide, each of said coupling means being adapted to be excited by energy in said waveguide of varying degrees of intensity depending on the position of said coupling means relative to the energy field in said waveguide and to excite in said waveguide energy of varying degrees of intensity depending on which of the respective dipoles receives energy of maximum intensity returned by a target to said antenna during the period that said exciting means is inoperative, and means coupled to said waveguide for determining the orientation of the maximum E-vector of received energy in said waveguide and consequently the angle of elevation of the target returning said returned energy.

7. A system comprising a plurality of dipoles aligned along a wave guide, means to couple successive dipoles to successive points within said wave guide, said points being characterized by an increased peripheral displacement from the aligned dipoles, means to excite said wave guide in the transverse electric mode with pulses of carrier wave energy, said means being aligned with said dipoles, and means circumferentially spaced from said exciting means to determine the angle of polarization of energy induced within in said wave guide by a pulse echo.

8. In a pulse echo system, an antenna comprising a parabolic reflector, a wave guide, a plurality of dipoles disposed along the surface of said wave guide and aligned with a longitudinal axis thereof, means to mount said wave guide and the array of said dipole perpendicular to the axis of said reflector, the uppermost of said dipoles being positioned at the focal point of said reflector, a plurality of wave guide probes to electrically connect each of said dipoles to said wave guide, the probe complementary to said uppermost dipole being substantially perpendicular thereto, successive probes being spaced increasingly greater peripheral distances from their respective complementary dipoles, the peripheral spread between the uppermost and the lowermost of said probes being less than 90 degrees, means to excite said wave guide in the transverse electric mode with pulses of carrier wave energy, said exciting means being aligned with said aligned dipole array, whereby a pulse of electromagnetic energy radiated by said dipoles may be directed from said reflector in an unsymmetrical pattern, and means to determine the polarization of a field set up in said wave guide by an echo resulting from the aforesaid radiated energy being reflected from a target back to said antenna, whereby the elevation angle of said target may be determined.

9. An antenna comprising waveguide means, a linear array of antenna elements, a number of probes situated within said waveguide, said probes situated within said waveguide, said probes

having different angular positions of entry into said waveguide with respect to a reference position, and means separately coupling each of said probes to a different one of said antenna elements.

10. An antenna system comprising a reflector, an array of spaced antenna elements juxtaposed to said reflector, a waveguide, an array of probes situated within said waveguide, said probes having different angular positions of entry into said waveguide with respect to a reference direction, and means coupling each of said probes to one of said antenna elements.

11. An antenna system comprising a reflector, a plurality of spaced antenna elements cooperating with said reflector, a waveguide, a like plurality of probes situated within said waveguide, said probes having different angular positions in

5
8
said waveguide, each of said probes being separately coupled to a corresponding antenna element, and means coupled to said waveguide to transmit energy to and from said waveguide.
